ALEXANDER MEISSNER, OF BERLIN, GERMANY, ASSIGNOR TO TELEFUNKEN GESELLSCHAFT FÜR DRAHTLOSE TELEGRAPHIE M. B. H., BERLIN, GERMANY.

ANTENNA.

Application filed May 12, 1927, Serial No. 190,697, and in Germany June 28, 1926.

The present invention relates to an antenna arrangement which is particularly suited for short-wave transmission and reception.

The invention consists in the employment 5 of a long horizontal antenna, whose length must be at least equal to one wave-length, though it is preferable to choose the same substantially longer so that a relatively great 10 number of half-waves of the working frequency will have a chance to arise along it. Now, according to the present invention, coils are inserted at intervals of a half-wave length along the said antenna wire, said coils being so dimensioned that the distribution 15 of current along them will also correspond to a half-wave length. In this way, the different horizontal wires will be in phase compared with one another, whereby increased distant action of the whole arrangement is insured.

The specification is accompanied by a drawing in which

Figure 1 represents an antenna embodying 25 my invention; and Figure 2 represents an antenna array according to my invention.

The coils inserted in the aerial wire, as shown in the drawing, serve for phase reversal, and the entire antenna acts in the same 30 way as a number of individual horizontal antennæ excited in phase would act taken together. Energy supply may be effected, for instance, at the central antenna wire, as indicated.

For the purpose of energy supply, if desired, a distinct coil may additionally be connected in each of the respective portions of the horizontal antenna.

Under certain circumstances, it may be 40 recommendable to combine a plurality of such antennæ to form an antenna system or array, as shown in Figure 2, in order to thus insure good directional characteristics for space radiation. In this case, it is necessary to excite 45 all of these antennæ at the proper relative phase angles, in dependence upon the desired directive action.

The different horizontal antennæ comprised in such a system or antenna array as 50 already described may also be arranged at different heights above ground, for this also exercises an influence upon the directive action.

In accordance with the invention I may 55 also provide the antennæ with reflection

means. The reflector may have the form of a parabolic mirror in whose focal line the antennæ are mounted. For the reflector any of the different and well-known forms of construction may be used; for instance, it 60 may consist of a continuous metallic mirror or else it may be formed of individual suitably tuned wires.

An antenna arrangement of the kind hereinbefore described may also be employed for 65 the reception as well as transmission of electrical oscillations.

I claim:

1. A horizontal antenna comprising a plurality of horizontal radiating and a plurality 70 of substantially non-radiating reactances connected alternately in series, each having an electrical length of a half wave.

2. A horizontal antenna comprising a plurality of horizontal half wave length radiating wires located end to end, and phase changing means connecting said wires in series with a change in phase sufficient to make the radiation from said wires co-phasal.

3. A horizontal antenna comprising a plurality of horizontal radiating wires, each a half wave in electrical length, located end to end, and an inductance a half wave in electrical length for connecting two of said radiating wires in series.

4. An antenna comprising a long horizontal wire and a plurality of poorly radiating reactors each a half wave in electrical length inserted in series with the wire and spaced an electrical half wave apart along 80 the wire.

5. A horizontal antenna array including a plurality of antennæ each comprising a plurality of horizontal radiating wires a half wave in electrical length connected in series 85 by inductances a half wave in electrical length, and a feed circuit including phase adjusting means for interconnecting said antennæ.

6. An antenna array for obtaining directional transmission and reception of short waves including a plurality of spaced horizontal antennæ arranged physically in parallel, and connected electrically in parallel by feed circuits including phase changing means 100 adjustable to obtain the desired directivity, each antenna comprising a plurality of horizontal radiating wires a half wave in electrical length, located end to end, and connected in series by inductances a half wave 105 110

in electrical length, whereby the radiators in each antenna radiate in phase, and the antennæ radiate in a phase relation dependent on the directivity desired.

- 5 7. An antenna array for obtaining directional transmission and reception of short waves including a plurality of horizontally spaced antennæ arranged physically in parallel and at progressively increasing heights
10 above ground, and connected electrically in parallel by feed circuits including phase

changing means adjusted to obtain the desired directivity, each antenna comprising a plurality of horizontal radiating wires a half wave in electrical length, located end to end, and connected in series by inductances a half wave in electrical length, whereby the radiators in each antenna radiate in phase, and the antennæ radiate in a phase relation dependent on the directivity desired. 15
